(57) **CLAIM**

The ornamental design for an arm positioning cushion, as shown and described.

DESCRIPTION

FIG. 1 is a perspective view of an arm positioning cushion shown in an engaged configuration, in accordance with our invention;

FIG. 2 is a right side view of the arm positioning cushion of FIG. 1.

FIG. 3 is a left side view of the arm positioning cushion of FIG. 1.

FIG. 4 is a top view of the arm positioning cushion of FIG. 1.

FIG. 5 is a bottom view of the arm positioning cushion of FIG. 1.

FIG. 6 is a back end view of the arm positioning cushion of FIG. 1.

FIG. 7 is a front end view of the arm positioning cushion of FIG. 1.

FIG. 8 is a perspective view of the arm positioning cushion in an extended or separated configuration.

FIG. 9 is a perspective view of another embodiment of the arm positioning cushion;

FIG. 10 is a right side view of the arm positioning cushion of FIG. 9.

FIG. 11 is a left side view of the arm positioning cushion of FIG. 9.

FIG. 12 is a top view of the arm positioning cushion of FIG. 9.

FIG. 13 is a bottom view of the arm positioning cushion of FIG. 9.

FIG. 14 is a back end view of the arm positioning cushion of FIG. 9; and,

FIG. 15 is a front end view of the arm positioning cushion of FIG. 9.

The broken lines illustrate portions of the arm positioning cushion which form no part of the claimed design.
